UNITED STATES PATENT OFFICE.

JOSEPH A. BURROWS, OF AKRON, OHIO, ASSIGNOR TO THE GOODYEAR
TIRE AND RUBBER COMPANY, OF AKRON, OHIO.

RUBBER-TIRE-SETTING MACHINE.

SPECIFICATION forming part of Letters Patent No. 698,446, dated April 29, 1902.

Application filed July 31, 1901. Serial No. 70,403. (No model.)

To all whom it may concern:

Be it known that I, JOSEPH A. BURROWS, a citizen of the United States, residing at Akron, in the county of Summit and State of Ohio, have invented a certain new and useful Improvement in Rubber-Tire-Setting Machines, of which the following is a specification.

My invention has relation to improvements in machines for placing or setting solid-rubber vehicle-tires having embedded longitudinal wires in channeled metallic tires mounted on vehicle-wheels.

The objects of my invention are to provide improved means for sustaining the wheel during the process of setting the tire, to adapt the machine to be used with the wheel in either a vertical or horizontal position, to provide new and improved devices for drawing the wires, and to provide an adjusting device to equalize their tension and generally to simplify the construction and reduce the number of working parts to a minimum.

To the accomplishment of the aforesaid objects my invention consists in the peculiar and novel construction, arrangement, and combination of parts hereinafter described and then specifically pointed out in the claims, reference being had to the accompanying drawings, which form a part of this specification.

In the accompanying drawings, in which similar reference-numerals indicate like parts in the different figures, Figure 1 is a front elevation of my improved machine; Fig. 2, a side elevation looking from the left of Fig. 1, with certain parts in section at the line xx of Fig. 1; Fig. 3, a section of a portion of Fig. 1 at the line yy ; Fig. 4, an enlarged view of a portion of the winding-drum to illustrate the wire-clamping device; Fig. 5, a section of the same at the line zz of Fig. 4, and Fig. 6 an enlarged detail of the wire-equalizing device and hereinafter described.

Referring to the figures, 1 is a metallic plate, which may be of cast-iron, arranged to be secured to a heavy plank 2 by bolts 3, 4, and 5. On the right and left ends of the plate 1 and integral therewith are projecting brackets 6 7 with their front faces in the same plane and parallel with the face of the plate 1, their adjacent ends diverging from each other at the top and rounded at the bottom,

the right bracket being the larger to form a support for winding mechanism to be described. In the brackets 6 and 7 are journaled like short shafts, the right arm 8 only being seen in Fig. 2, which short shafts bear integral heads 9 and 10, having in their front faces like channels to receive and fit the inner members 11 and 12 of the wire-clamping jaws, 60 which latter are retained therein by set-screws 13 and 14, respectively, and are hereinafter more fully described. In the upper end of the jaw 12 is a pivot 15, which bears a nut in which runs a screw 16, secured against longitudinal movement in a supporting-block 17 and provided with a hand-wheel 18, by which it is turned. In the upper end of the jaw 11 is a like pivot 19, bearing a similar nut (not seen) in which runs a screw 20, having its 70 ends revolvably secured in a block 21.

By the foregoing devices, the jaws 11 12 may be rocked on the shaft 8, and the corresponding shaft in the right bracket, to bring the ends of the wires into position for brazing as hereinafter described.

Through the lower ends of the jaws 11 12 are bolts 22 23, by which the outer jaws 24 25 are flexibly connected therewith and intermediate plates 26 27 retained between them. In the upper ends of the outer jaws 24 25 are pivotally mounted cam-levers 28 29, arranged to bear against the upper ends of the jaws 11 12 as the levers are rocked downward and force apart the upper ends of the 85 inner and outer jaws, and thus compress their lower ends. The adjacent faces of the outer and inner jaws and the interposed plates have corresponding oppositely-disposed grooves 30 below the bolts 22 23 to form 90 gripping devices for the wires, while the jaws 11 and 25, with the plate 27, have similar grooves 52 above the bolt to permit the wires from the opposite jaws to freely pass to the winding-drum now to be described.

In the extension of the bracket 6 is a wrist 31, on which is revolvably mounted a worm-wheel 32, in which meshes a worm 33, running in supports 34 35 and turned by a hand-wheel 36. On the face of this worm-wheel is a drum 37, provided with a wire-gripping device constructed in the following manner: In one side of the drum 37 is a recess (shown in Figs. 4 and 5) in which is snugly fitted the clutch of

a short solid cylinder 38, having in the upper face a truncated wedge-shaped channel 39, from the bottom of which channel a slot 40 extends to the other face. In the channel 39 5 is a wedge 41 enough smaller than the channel to permit wires to lie freely on each side when it is drawn toward the broader part and to engage and clamp them when it is drawn in the opposite direction, and this wedge is 10 retained against dislodgment by a screw 42, that passes up through the slot 40.

On the periphery of the drum 37, and preferably about opposite the wire-gripping device just described, is the tension-equalizing 15 device, (shown in enlarged detail in Fig. 6,) and which consists of a post 43, having the upper end forked and in which is pivotally mounted a rocking lever 44, which stands transversely to the wires and has a central 20 upwardly-extending finger 45, preferably triangular in form, as shown, and two lateral upwardly-curved fingers 46.

To adapt this apparatus to operate when the wheel stands horizontally, I provide a 25 two-armed bracket 47, secured to the plank 1 and having a central cylindrical part 48 with an internal longitudinal screw-threaded opening in which runs a screw 49, operated by a hand-wheel 50 and bearing at its outer 30 end a revolubly-mounted fork 51 to engage and support the wheel-felly.

In operation when it is intended to have the wheel stand vertically during the setting of the tire the wheel is placed against the 35 plank 2, with the felly 53 resting in the fork 51, and adjusted in proper relation to the clamping-jaws by the hand-wheel 50 and screw 49, so that the jaws 11 12, with their oppositely-disposed members, will enter the channel of the metallic tire 54. The rubber tire 55 is then placed in the channeled tire 54 and the wires from its right end secured in the right clamping-jaws by rocking down the lever 29. The wires from the opposite end of 40 the rubber tire are then passed freely between the left jaws, through the opening formed by the grooves 52, over the opposite lateral fingers 46 of the rocking lever 44, to and into the clutch in the drum 37 on opposite sides of 45 the wedge 41, which by a slight push forward clamps them. To insure this clamping, the sides of the channel 39 in the cylinder 38 may be slightly grooved to more securely hold the wire, and the sides of the wedge 41 may be 50 corrugated where great tension is required. The drum 37 is then turned, by means of the worm-wheel 32 and worm 33, to wind the

wires thereon until sufficient tension has been secured. In this portion of the process the rocking lever 44 performs an important function in this that the wire having the greatest tension will bear down the end of the lever over which it passes, and thus raise and necessarily increase the tension of the other until the tension on each is equal. When the 60 desired tension has been secured, the left jaws are closed upon them and the wires cut at such distance as will permit sufficient length for lapping and brazing. In this process the clamping-jaws also perform the function not only of holding the wires preparatory to and during the process of brazing, but of assisting in regulating their direction, so that their point of union may be peripheral to the line they occupy about the wheel. 65

The operation just described refers to the process where the wheel stands wholly or nearly vertical; but the same process is used where the plank 1 and the wheel lie horizontally, excepting that in such cases the bracket 80 47, screw 49, and their associated parts are not needed.

Having thus described my invention, what I claim is—

1. In a rubber-tire-setting machine having 85 gripping devices for holding the wires for brazing and a winding-drum to draw said wires, and means for turning said drum, of a regulating device to equalize the tension of 90 said wires located between said drum and gripping device consisting of a pivoted lever having its opposite arms arranged to sustain the wires, substantially as shown and described.

2. An improved rubber-tire-setting machine 95 consisting of a metallic plate having opposite offset brackets with their faces in the same plane and parallel with the face of said plate, with wire-gripping devices pivotally mounted in said brackets, means for rocking said devices on their pivots, a winding-drum provided with clutch mechanism to grasp said wires and a pivoted lever interposed between said drum and gripping devices having opposite arms to support said wires, and a worm-wheel and worm to turn said drum, substantially as shown and described. 100 105

In testimony that I claim the above I hereunto set my hand in the presence of two subscribing witnesses.

JOSEPH A. BURROWS.

In presence of—

FLORENCE C. DUN,
C. E. HUMPHREY.
